WAVE FILTER IMPEDANCE-COUPLED AMPLIFIER

Application filed March 19, 1928. Serial No. 262,880.

This invention relates to a vacuum tube amplifier for use in connection with radios, telephone repeaters, television, picture transmission, or any place where a vacuum tube amplifier is required to amplify a definite band of frequencies.

The principal object of the invention is to provide a wave filter in the plate circuit of a vacuum tube.

10 The invention possesses various objects and features of advantage, some of which, with the foregoing, will be made manifest in the following description of the preferred form of the invention which is illustrated in the 15 drawing accompanying and forming part of the specification.

It is to be understood that it is not intended to limit the invention to the embodiment shown by said drawing and descriptions, as 20 variations may be adapted within the scope of the invention as set forth in the claims.

In the accompanying drawing:

Figure 1 is a diagrammatic drawing showing a preferred method of coupling a wave 25 filter to the vacuum tube.

Figure 2 is a diagrammatic drawing illustrating the same principle as shown in Figure 1, but used in connection with a four element tube.

30 Figures 3, 4 and 5 are drawings illustrating some of the different kinds of wave filters that may be used in the invention.

This type of amplification comes under the general class of impedance-coupled amplifiers.

35 A common example of this is resistance coupling in which the plate current is fed through a high resistance, that is a resistance several times the plate resistance of the tubes, and the energy transfer to the next tube or to

40 the output tubes takes place through a condenser which must be large enough to have an impedance that is low compared to the output impedance for the frequencies to be amplified. This requires a very high voltage source for plate current and is very inselective with regard to the frequencies amplified and thus is very uneconomical and hard to control.

Another method uses a heavy inductance in 45 the plate circuit. This has the advantage of

requiring a plate supply having a voltage very little greater than that required for the tube, but its behavior with frequency is poor, as the inductance presents a different impedance to every different frequency, and hence 55 every different frequency is differently amplified.

In the proposed system a system of inductances and capacities known as a wave filter is used. This system has the property of passing energy perfectly, that is, presenting zero 60 impedance to certain frequencies and of presenting infinite impedance, that is allowing no energy to pass on all other frequencies.

The frequencies which this filter will not pass will be passed on to the next tube (or the output) perfectly, having been amplified in voltage by a factor equal to the voltage amplification factor of the tube. Any wave filter may 65 be used which will pass direct current to the plate of the tube. For instance, in Figure 3 a low pass filter is shown. If it is made with a cut-off frequency at ten cycles for example, every frequency above ten cycles will be 70 equally amplified. Figures 4 and 5 are

75 optional designs of band elimination filters, the condensers and inductors of which may be so chosen that they will not pass certain frequencies, for example of from one thousand to two thousand in which case all frequencies between one thousand and two thousand cycles will be equally amplified, while the frequencies outside of this band will not be amplified at all.

80 It is to be understood that the present invention exists, not in the type of filter used, but in the location of the filter in the plate circuit where its characteristic impedance can be made equivalent to the impedance into which it feeds, viz. the plate impedance of the tube. Practical considerations, which 85 prevent a filter being made having a characteristic impedance equivalent to the grid impedance of a tube, allow the impedance of a filter to be easily matched to the plate impedance of a tube. This is important, as the operation of a filter depends on its characteristic impedance being equivalent to impedance of the device into which it works.

90 In Figure 1 there is shown an illustration 100

95

100

of the application of this principle to ordinary amplifying tubes. A—A designates a battery for supplying the heating current for the filaments of the vacuum tubes VT—1 and VT—2. B—B designates a battery for supplying the plate voltage. Batteries C 1 and C 2 supply through the resistance R 1 and R 2, respectively, the necessary blocking potential so that the tubes will always operate on the straight portion of their characteristic curves.

The numerals 6 and 7 designate conductors where the current to be amplified is applied. The condenser C 3 between the conductor 6 and the grid 8 of vacuum tube VT—1 is a blocking condenser to prevent direct potentials in the input from disturbing the equilibrium potential of the grid 8. The battery B supplies current through the filter F—1 to the plate 9. Variations in voltage on the terminal 6 and 7 are passed through C 3 to the grid 8. This causes similar variations in the plate current of the tube VT—1. If these variations are of a frequency such that they are passed by the filter F—1, there will be no appreciable change of the potential at the plate 9. If, however, the frequency of these pulses are such that they are rejected by the filter F—1, the potential at the plate 9 will vary in exact unison with that at the grid 8, but with an amplitude many times that at the grid 8. These amplified variations of potential will pass through the condenser C 4 and vary the potential on the grid 10 of the vacuum tube VT—2 and a similar action occurs in the vacuum tube VT—2 as hereinbefore explained in the vacuum tube VT—1, so that frequencies which are rejected by the filters F—1 and F—2, if they are impressed on the terminals 6 and 7, will appear at the plate 11 of the vacuum tube VT—2, greatly increased in amplitude, and will pass through the condenser C 5 where they may be fed from the terminals 12 and 13 to any device which they are to operate.

Figure 2 involves the same principles as illustrated in Figure 1 with the exception of the introduction of the grids G—1 and G—2, 50 in the vacuum tubes VT—1 and VT—2, respectively, connected to the battery intermediate terminal marked B—1, which increase the amplification of the tubes and decrease the possibility of oscillation feed back in the tubes.

Having thus illustrated and described a certain form of construction and arrangement of parts pertaining to the invention, it is to be understood that any type of wave 60 filter may be used and that the various parts may be arranged in any suitable manner, the present illustration not indicating the only arrangement that may be made; and it is desired to include in this application for 65 Letters Patent of the United States of

America, any and all patentable novelty that exists in the invention disclosed and all that comes within the principle of the invention as set forth in the claims hereinafter mentioned.

What is claimed is:

1. A vacuum tube amplifier comprising at least two tubes, said two tubes being coupled from the plate of one to the grid of another by means of a condenser, said plate being connected to its respective filament through a band-elimination filter and a source of voltage, said grid being connected to its filament in the usual manner, and having a mid-series termination at said plate.

2. A vacuum tube amplifier comprising at least two tubes, said two tubes being coupled from the plate of one to the grid of another by means of a condenser, said plate being connected to its respective filament through a band-elimination filter and a source of voltage, said grid being connected to its filaments in the usual manner, and said band-elimination filter comprising at least one and one-half sections, the said band-elimination filter being connected to the plate end at a mid-series termination and to the voltage source at a mid-shunt termination.

3. A vacuum tube amplifier comprising a plate circuit current coupling device consisting of a low-pass filter having a mid series termination adjacent said plate and a parallel utilization circuit passing only alternating current components.

In testimony whereof, I hereunto affix my signature.

WINFIELD W. SALISBURY.
